Primary Examiner — Jennifer Rivard*Assistant Examiner* — April Rivas*(74) Attorney, Agent, or Firm* — Workman Nydegger(57) CLAIM

The ornamental design for a cinchable carrying bag, as shown and described.

DESCRIPTION

FIG. 1 is a top perspective view of a cinchable carrying bag in an unfolded configuration;

FIG. 2 is a bottom perspective view thereof;

FIG. 3 is a bottom plan view thereof;

FIG. 4 is a rear elevation view thereof;

FIG. 5 is a top plan view thereof;

FIG. 6 is a front elevation view thereof;

FIG. 7 is a right side elevation view thereof;

FIG. 8 is a left side elevation view thereof; and,

FIG. 9 is a perspective view of the cinchable carrying bag of FIG. 1 in a folded configuration.

The broken lines depicted in FIGS. 1-9 illustrate portions of the cinchable carrying bag that form no part of the claimed design.

1 Claim, 6 Drawing Sheets(56)
